UNITED STATES PATENT OFFICE.

JAY A. HEIDBRINK, OF MINNEAPOLIS, MINNESOTA.

APPARATUS FOR DELIVERING A MIXTURE OF GASES.

1,265,910.

Specification of Letters Patent. Patented May 14, 1918.

Application filed September 26, 1912. Serial No. 732,455.

To all whom it may concern:

Be it known that I, JAY A. HEIDBRINK, a citizen of the United States, residing at Minneapolis, in the county of Hennepin 5 and State of Minnesota, have invented certain new and useful Improvements in Apparatus for Delivering a Mixture of Gases, of which the following is a specification.

My invention relates to an apparatus for 10 delivering a mixture of two or more gases to be used as an anesthetic. The invention has for its object primarily to deliver to a gas bag a mixture of two gases, such, for example, as nitrous oxide and oxygen in proper 15 proportions for producing anesthesia as in a given patient. And the apparatus embodying my invention provides means for ready and instant control of the flow of gas so that the proportions of gases may be 20 varied at will, but such that when a given proportion of gas is desired more or less of gas mixture in such proportion may be delivered at will to the gas bag and the flow of gas in that proportion be continued in 25 definitely whatever the rate of flow.

It is also an object of my invention to provide means whereby the mixture of gases may be cut off and a single gas such as pure oxygen be fed to the respirator. I also provide 30 novel means for warming the gas as it passes from the container to the gas bag as well as means for permitting re-breathing where such may be desirable.

The full objects and advantages of my 35 invention will appear in connection with the detailed description thereof and are particularly pointed out in the claims.

In the drawings, illustrating the application 40 of my invention in one form,—

Figure 1 is a side elevation of a gas administering apparatus embodying my invention. Fig. 2 is a plan view of the same. Fig. 3 is a fragmentary sectional elevation on line 3—3 of Fig. 2. Fig. 4 is a sectional view of the valve mechanism shown in Fig. 3 viewed at right angles thereto. Fig. 5 is an enlarged view of the scale for indicating the valve opening. Fig. 6 indicates a form of marking for the dials of the gages. 45 An ordinary base 10 has secured centrally thereon a standard 11 threaded into a socket 12 in a table 13 having a pair of arms 14. Each of the arms 14 has secured thereto a crossbar 15 provided with a valved aperture 50

16, and each crossbar has at the end thereof a yoke 17 within which the heads 18 of gas containers 19 are adapted to be positioned and secured in communication with the channel of aperture 16 by means of screws 20, the flow of gas from the containers 19 being regulated by hand screws 21. The yokes 17 have a nipple 22 positioned to enter a socket in the heads 18 and the screws 20 force the said nipple within said socket in a gas tight manner. The containers 19 on one side of the machine will contain nitrous oxide, those on the other side will contain oxygen, where the mixture of gases is to be nitrous oxide and oxygen. As shown in the drawings, containers at the 55 right are charged with nitrous oxide and those at the left with oxygen. Within a socket 23 formed on the top of table 13 is secured by threading or otherwise a short standard 24. Supported upon the standard 60 24 is a casting 25 having a mixing chamber 26 from which extends a passage-way 27. The passage-way 27 is provided with a perforated partition 28, a flap valve or vibrating disk 29 operating to close the apertures 65 in partition 28 when the pressure from outside of mixing chamber 26 exceeds the pressure inside said chamber, and correspondingly moving to open said apertures when the higher pressure is within chamber 26. 70 The disk 29 is slidably mounted on a spindle 75 30 which extends through the partition 28, said spindle being provided with an inside shoulder 64 adapted to set within an aperture for receiving the same in the partition 80 28. The spindle 30 also has an outer shoulder 31 spaced from the inner shoulder 64 so that the disk 29 is permitted to vibrate 85 on spindle 30 between the shoulders 64 and 31, a distance sufficient to permit ready passage of the mixture during inhalation. The spindle 30 has on the inner end, inside of partition 28, a cap 32 formed to cover the apertures in partition 28 when said cap is brought into engagement therewith. A 90 spring 33 surrounds the spindle 30 and engages a seat in the partition 28 and another seat in the cap 32, operating to push said cap and the spindle inwardly so as normally 95 to bring the shoulder 64 into its recess in the partition 28, in which position disk 29, at its inward movement, will connect with partition 28 and close the apertures therein 100 105

from the outside, thereby preventing re-breathing. In the position of the parts, as shown in Fig. 3, the cap 32 will just engage the periphery of a cam member 34 protruding within the passage-way 27 and operated by a thumb nut 35. Turning the thumb nut will rotate the cam member, moving the cap and spindle, with the shoulders thereon, outward so that shoulder 64 is brought out of its seat and diaphragm 29 can no longer, on its inward movement, engage partition 28 and close the apertures therein. This will permit re-breathing of the anesthetizing mixture; thus the exhalations of the patient may pass through the apertures in partition 28 and into the container or gas bag 65 which opens through connection 66 into passage-way 27 inside of partition 28. The extent of re-breathing may be varied by varying the position of spindle 30 and shoulder 64 so that the diaphragm may approach more or less close to partition 28, thereby producing a greater or less opening for re-breathing. If it is desired to close entirely the connection from the respirator with the mixing chamber, cam 34 may be operated to force the cap 32 into engagement with partition 28, thereby closing the apertures therein.

10 The gas from the containers 19 is admitted to the passage-way 16 by hand wheels 21, as before stated. From the passage-way 16 the nitrous oxid gas passes through a passage-way 36 into a reducing valve mechanism 37 of well known construction. The oxygen gas similarly passes through a connection 38 into reducing valve structure 39. From the reducing valve 37 the nitrous oxid gas is conducted by a passage-way 40 to a valve head 41 secured to the top of the walls of chamber 26, the connection 40 entering a short chamber 42, as clearly shown in Fig. 4, and being provided with a cut-off valve 43, as indicated in Fig. 1. Similarly 15 the oxygen passes through a connection 44 from reducing valve 39 to an independent chamber 45 in the valve head 41, a cut-off valve 46 being also provided to shut off oxygen from chamber 45.

20 The head 41 has the bottom wall thereof forming the roof of the chamber 26, which bottom wall or roof is milled smooth and true. From the chamber 42 an aperture 47 extends into chamber 26 and from chamber 25 45 an aperture 48 extends into chamber 26. Different proportions of nitrous oxid and oxygen may be employed for an anesthetizing mixture, according to the experience and practice of the operator and the character of anesthesia desirable to produce. In general, it may be said that the proportions of oxygen and nitrous oxid to produce analgesia, or the low form of anesthesia, in which the sensory nerves are inactive although reason is retained by the patient,

would be something like four parts of nitrous oxid to one part of oxygen. I prefer, therefore, to form the apertures 47 and 48 of such size in relation to the form of valve closure employed that, when the pressures at which the two gases are delivered are equal, four times as much nitrous oxid will pass to the mixing chamber as oxygen. Many different forms of valve closures may be employed to effect this result. The preferred form shown herein, which is subject to easy control, comprises a disk 49 on a shank 50 threaded into the valve head 41, the disk 49 being in the chamber 26 and coming below the apertures 47 and 48, the surface of the disk adjacent to said apertures and the bottom wall of head 41 being milled smooth and true so that when said disk is drawn up against the bottom wall, it will fit tightly therewith and wholly cut off a flow of gas through the apertures 47 and 48. The threaded shank 50 has in the outer end thereof a thumb nut 51 by which the same may be turned, turning of the shank 50 having the effect of moving the disk 49 away from or toward the bottom of the head 41.

20 The cut-off valves 43 and 46 are formed in short pipe sections 52 and 53 into which the connecting pipes 40 and 44 respectively, deliver, and the pipe section 52 has at the end thereof a gage 54, at all times subject to the pressure of gas delivered from the reducing valve 37. Similarly the pipe section 53 connects with a gage 55 subject at 100 all times to the pressure of gas delivered from reducing valve 39. The reducing valves are subject to complete manual control by means of a hand nut 56 on valve 37 and a hand nut 57 on valve 39. The pressure of the gas being delivered from each of the reducing valves (that is, nitrous oxid from valve 37 and oxygen from valve 39) may thus be instantly and accurately regulated.

25 The apertures 47 and 48, as here shown, have a relative delivery capacity of four to one, and means is here provided on the respective gages, specifically as shown on the oxygen gage, by which the proportions of the oxygen gas in any of the mixtures going to the patient may be immediately determined by inspection. It will be noted that the gages 54 and 55 for nitrous oxid and oxygen respectively, will be in all respects identical, and each may suitably be such as will register a maximum pressure of six (6) pounds, which is such a gage as would be practicably desirable in an apparatus of this character. The scales on each of the gages will, of course, comprise the usual figures, running from one pound to 6 pounds, and at least subdivided into fourths, for indicating pressures from zero to one-fourth pound and upward to six 130

potinds. The nitrous oxid scale in practice will show only the pressures at which this gas is being delivered. Upon the oxygen gage I form a second scale comprising figures up to twenty four or higher for indicating the percentage of oxygen in the mixture of gases being delivered at the indicated oxygen pressure when the pressure of the nitrous oxid as indicated upon its scale 5 is at a predetermined point; that is the needle of the oxygen gage will indicate the delivery pressure of oxygen on the pressure scale and at the same time, will indicate on the second scale the percentage of oxygen 10 being delivered in the mixture of gases passing to the gas bag and respirator. This percentage scale is, for any one gage, developed only for one fixed or predetermined pressure of the nitrous oxid as indicated by the 15 nitrous oxid pressure gage scale. In the scale construction shown in Fig. 6 of the drawings, the oxygen percentage scale is developed to show the percentages of oxygen in the mixture of gases going to the patient 20 when the nitrous oxid pressure, as shown by the nitrous oxid gage, is at five (5) pounds; this being a satisfactory and convenient pressure for nitrous oxid. It will be understood that the pressure indication 25 of either gage is controllable at will by means of the thumb screws 56 and 57 of the reducing valves, so that it will always be practicable to have a fixed reading upon the nitrous oxid gage, this being, as shown, five 30 (5) pounds. In varying the proportion of oxygen in the mixture, it will usually only be necessary to vary the pressure at which the oxygen is delivered to the mixing chamber, and such variation will not only show 35 on the gage the pressure at which oxygen is being delivered, but on the second scale will show the actual percentage of oxygen going into the mixture which the patient is breathing. This is true, in the gage shown in Fig. 40 45 5 only when the gage for nitrous oxid is set to deliver nitrous oxid at a pressure of five (5) pounds, to which the secondary scale for percentages of oxygen is graduated. It will thus be seen that the proportion of gases 50 going to the patient is controllable at will and instantly by the operator through the thumb screws 56 and 57, although practically where a mixture is delivered, owing to the ratio of size of the delivery apertures 55 of the respective gases, there will always be a much greater quantity of nitrous oxid in the mixture than of oxygen. A connection 58 is provided extending from reducing valve 39 to the passage-way 59 leading from 60 beyond the diaphragm 28 to the respirator, which connection is controlled by a cut-off valve 60. If it is desired at any time to give the patient pure oxygen to effect quick stimulus, the screw 35 and cam 34 may be 65 turned to close the openings from passage

27 through diaphragm 28 and valve 60 opened, admitting oxygen directly to the patient.

The volume of mixture being delivered through mixing chamber 26 is absolutely 70 controlled by the thumb nut 51 operating the valve disk 49. As shown in Fig. 5, the shank 50 of the thumb nut 51 is provided with a pointer 61 which covers a scale disk 62 on the top of the portion 41 forming the 75 valve chamber. Pins 62' and 63 limit movement of the pointer 61 to a little more than half a full turn of screw 51, which amount of turning will open the apertures 47 and 48 for maximum delivery of the gas in whatever proportion is indicated by the relative pressures shown on the two gages 54 and 55. The second pin 63 is necessary since, if the valve were open beyond the maximum capacity of the smaller aperture, the proportion of gases being delivered would no longer remain as indicated, but gas from the larger aperture would be delivered at a relatively greater rate than from the smaller aperture. The pins 62' and 63 are so positioned relative to the right line movement of valve disk caused by the thread of shank 50 as to produce the above indicated result. It is obvious that if the reach of the threads on shank 50 were made sufficiently small, a 80 single pin 62' might be employed to be engaged on either side by the pointer 61 and the thumb screw 51 and thereby be capable of practically a complete turn. In this particular it will be noted that a very slight turn of screw 51 will open to an appreciable extent the delivery apertures 47 and 48. When, however, any opening is made the respective gases will flow into the chamber 26 in the proportion indicated, and will always 85 flow in that proportion whether the valve is opened little or much of its maximum capacity. The movements of the valve are controlled with the greatest ease by the operator and will always result in delivering the exact proportion of gas which is desired. The operation of the thumb nut 35 and cam 34 regulating the movement of head 32 and spindle 30 will determine the extent of re-breathing and will regulate this as desired. 90 If the disk 29 has a relatively large amount of freedom of travel upon the spindle 30 and yet can always come back against diaphragm 28, there will be little or no re-breathing. If, however, cam 34 is turned so 95 as to push the shoulder 64 on spindle 30 far enough out so that disk 29 cannot come back into contact with diaphragm 28, re-breathing will be permitted in proportion to the distance away from diaphragm 28 at which 100 disk 29 is being held, it being noted of course that the usual gas bag 65 opens through a connection 66 into passage-way 27 extending from mixing chamber 26. 105

As clearly shown in Fig. 3, the mixing 110

chamber 26 is oblong in shape, and within said chamber and spaced from the inner walls thereof is a closed thin walled casing 67 opening outwardly through an aperture in the end wall 68 of chamber 26. Within the interior of casing 67 is inserted an ordinary incandescent electric light 69 or other electric heating device, as may be desired. The gases entering through apertures 47 and 48 will pass over the edges of valve disk 49 and flow around the heated casing 67 on the way out through passage 27, and are thereby warmed to the desired extent before breathing. In certain cases it is desirable to administer ether or other anesthetic either in combination with one or both of the gases forming the usual mixture, or separately, and to accomplish this I provide an ether cup 70 having a connection through a tube 71 into chamber 26, said ether cup being provided with a dropper mechanism 71' of usual construction. The ether will drop upon the heated casing 67 and vaporizing, will pass into the respirator tube and gas bag either separately or as part of the mixture, according as the same may be used.

I claim:

1. A gas administering device having a mixing chamber, means for supplying thereto from independent sources of supply a plurality of gases each under pressure and in fixed proportions at their respective pressures, and means for definitely regulating and determining the aggregate volume of flow of said gases into the mixing chamber at their respective pressures while maintaining said fixed proportions.

2. A gas administering device having a mixing chamber, means for supplying thereto from independent sources of supply a plurality of gases each under pressure and in fixed proportions at their respective pressures, means for controlling the respective pressures at which the several gases are delivered to the mixing chamber, and means for definitely regulating and determining the aggregate volume of flow of said gases into the mixing chamber at their respective pressures while maintaining said fixed proportions.

3. A gas administering device having a mixing chamber, means for conducting independently and through separated openings a plurality of gases into said chamber in fixed relative proportions, an integral valve member controlling the openings for both of said conducting means and normally fixed in relation to the points of discharge therefrom, and means to move the valve uniformly in reference to said discharge openings to vary at will the aggregate volume of flow of gases into the mixing chamber while maintaining their respective delivery proportions constant.

4. A gas administering device having a mixing chamber provided with a plane-faced wall and having independent separated apertures opening through said wall, means for conducting a plurality of gases from independent sources of supply independently through each of said apertures into the chamber in predetermined relative proportions, a closure having a plane-surfaced wall held fixed in spaced parallel relation with said wall of the chamber for controlling the flow of gases through said apertures, and means to move the closure bodily so that the plane face thereof will be caused uniformly to approach or recede from said wall to vary at will the aggregate flow of gases into the mixing chamber while maintaining their respective delivery proportions constant.

5. A gas administering device having a mixing chamber, a valve head having a plane surface on one side forming a part of a wall of said chamber, said valve head being provided with a plurality of independent cavities and having independent apertures leading from said cavities into the mixing chamber, means for conducting a different gas into each of said cavities and to the apertures, a closure disk within the mixing chamber having a smooth face co-operating with said plane-surfaced wall to control all of said apertures, and means under the control of the operator to move the closure disk bodily and uniformly toward and from said apertures.

6. A gas administering device having a mixing chamber and a plurality of separated delivery apertures extending through a wall of said mixing chamber, means for conducting different gases at fixed relative pressures independently into the mixing chamber through each of said apertures, a single unitary valve member within the mixing chamber having portions co-operating with and controlling the delivery openings of the respective apertures, and means to move the valve member so that said portions will be caused uniformly to approach and recede from the respective apertures.

7. A gas administering device having a mixing chamber and a plurality of separated delivery apertures extending through a wall of said mixing chamber, said apertures varying in size for delivering fixed relative proportions of the gases when the delivery pressures of the gases are equal, means for conducting different gases at fixed relative pressures independently into the mixing chamber through each of said apertures, a single unitary valve member within the mixing chamber having portions co-operating with and controlling the delivery openings of the respective apertures, means to move the valve member so that said portions will be caused uniformly to approach

and recede from the respective apertures, and means limiting movement of said valve member so that the maximum movement thereof away from the apertures will open 5 the smallest aperture only to its maximum capacity.

8. A gas administering device having a mixing chamber formed with a smooth-surfaced wall, a pair of separated delivery apertures extending through said wall, said apertures having relative areas at said surface of one to five, means for independently conducting into the chamber nitrous oxid through the larger aperture and oxygen 10 through the smaller aperture at fixed relative pressures, a valve plate within the mixing chamber having a plane-surfaced face co-operating with said chamber face and apertures, means for definitely and uniformly 15 moving said plate toward and from said apertures and the wall face predetermined varying distances to regulate the flow of gases from said apertures, and means limiting said movement so that the maximum 20 movement thereof away from the apertures will open the smallest aperture only to its maximum capacity.

9. A gas administering device comprising separate containers of fluid under pressure, 30 a mixing chamber and means for conducting said fluids independently thereto through separate discharge openings, a unitary valve member within the chamber adapted to block both of said openings, and means to 35 move the valve member definitely and uniformly through predetermined distances so that the opening-blocking portions thereof shall be caused to recede from or to approach both said openings uniformly.

10. A gas administering device comprising separate containers of fluid under pressure, a mixing chamber provided with a plane-faced wall and having independent apertures opening through said wall, means 45 for conducting the gases from said containers independently through each of said apertures into the chamber, a thumb-nut having a threaded shank extending through said wall and into said chamber adjacent said 50 apertures, a closure plate secured to the end of said shank in said chamber and having a plane face adjacent and parallel with the plane face of the wall and overlying said apertures so that rotation of the shank and 55 plate by means of the thumb-nut will move the plate bodily away from or toward the face of said wall and said apertures to vary at will the aggregate volume of flow of gases into the mixing chamber without varying 60 their relative delivery pressures.

11. A gas administering device comprising separate containers of fluid under pressure, a mixing chamber, means for conducting the gases independently from said containers and delivering them into said chamber

ber so that the relative proportion of the gases will be unchanged by the delivery means and can be varied only by varying the relative delivery pressures of the gases, means to regulate at will the delivery pressures of each of said gases, means to indicate the pressures at which said gases are delivered for determining the relative proportions of gases going into the chamber and the quality of mixture produced, and means 70 for regulating and controlling the aggregate volume of flow of gases into the mixing chamber while maintaining unchanged the proportions determined by the delivery and pressure-controlling means.

12. A gas administering device comprising a pair of separate containers one having nitrous oxid and the other oxygen stored under pressure therein, a mixing chamber, means for conducting said gases independently from the containers to the mixing chamber, means in said conducting means for varying at will the relative pressures at which said gases are delivered, independent 85 gages each having connection with one of said conducting means and each provided with a scale for indicating the pressure at which gas is being delivered, the oxygen gage being provided with a scale for indicating the percentage of oxygen in the mixture of gases being delivered at the indicated oxygen pressure when the pressure of the nitrous oxid as indicated upon its scale is at a predetermined point.

13. A gas administering device comprising a pair of separate containers one having nitrous oxid and the other oxygen stored under pressure therein, a mixing chamber, means for conducting said gases independently from the containers to the mixing 100 chamber including separated delivery apertures having different relative discharge areas for delivering proportions of the respective gases such as to produce a mixture of the desired quality when the pressures of 105 the gases are equal, means in said conducting means for separately regulating the delivery pressures of the respective gases, means for determining the delivery pressures of said gases so that said pressures may 110 be equalized, and means limited in operation to permit no more than maximum flow of gas through the smallest aperture for varying the aggregate volume of flow of said gases into the mixing chamber while maintaining the proportions determined by the delivery apertures and the delivery pressures 115 of the gases.

14. A gas administering device having a mixing chamber, a respirator tube connected 125 with the mixing chamber, a disk therein, a gas bag having connection with the mixing chamber on the inner side of said disk, and means controlled by the position of the disk so as to permit breathing of gas mixture 130

- from the mixing chamber at all times and to prevent or permit, as desired, entrance of the exhalations of the patient to the gas bag and consequent rebreathing of the gas mixture.
- 5 15. A gas administering device having a mixing chamber, a respirator tube connected with the mixing chamber having a perforated partition, a gas bag having connection 10 with the mixing chamber on the inner side of said partition, a disk normally coöperating with said partition to open and close communication with the mixing chamber and gas bag during breathing so as to permit 15 breathing of the gas mixture and prevent rebreathing, and controllable means for holding said disk spaced from the partition during exhalation of the patient to permit rebreathing.
15. 16. A gas administering device having a mixing chamber, a respirator tube connected
- with the mixing chamber having a perforated partition, a gas bag having connection with the mixing chamber on the inner side of said partition, a disk normally coöperating 25 with said partition to open and close communication with the mixing chamber and gas bag during breathing so as to permit breathing of the gas mixture and prevent rebreathing, a spindle on which said disk vibrates between fixed stops, and controllable means for moving said spindle bodily endwise so as to position the stops thereon so that the disk will be held spaced from said partition during exhalation to permit rebreathing of gas mixture. 30
- 35

In testimony whereof I affix my signature in presence of two witnesses.

JAY A. HEIDBRINK.
